UNITED STATES PATENT OFFICE.

JOHN M. LARSON, OF CHICAGO, ILLINOIS, ASSIGNOR TO NATIONAL REGULATOR COMPANY, OF CHICAGO, ILLINOIS, A CORPORATION OF ILLINOIS.

HIGH-PRESSURE STANDARD REGULATOR.

1,376,948.

Specification of Letters Patent.

Patented May 3, 1921.

Application filed June 2, 1917. Serial No. 172,535.

To all whom it may concern:

Be it known that I, JOHN M. LARSON, a citizen of the United States, residing at Chicago, in the county of Cook and State of Illinois, have invented new and useful Improvements in High-Pressure Standard Regulators, of which the following is a full, clear, concise, and exact description, reference being had to the accompanying drawing, forming a part of this specification.

My invention relates to improvements in high pressure standard regulators, and has for its object the production of a device that will operate in a high pressure system with substantial accuracy and without danger of breaking.

A further object is the production of a device which will act gradually and sensitively, and of such simple construction as not to be liable to disarrangement of parts.

These and such other objects as may hereinafter appear are attained by my device, embodiments of which are illustrated in the accompanying drawings in which—

Figure 1 represents a front elevation of my device with a portion broken away;

Fig. 2 represents a sectional view on the line 2—2 of Fig. 1, looking in the direction indicated by the arrows; and

Fig. 3 represents a sectional view on the line 3—3 of Fig. 2, looking in the direction indicated by the arrows.

Like numerals of reference indicate like parts in the several figures of the drawings.

Referring now to the drawings, 4 represents a pipe from a source of steam pressure controlled by a hand valve (not shown); 5 represents a plug; 6 a strainer; 7 the main gage; 8 the drip cock from the strainer; 9 the main cylinder casting; 10 a drip pipe from the cylinder; 11 a hand valve adapted to regulate the pressure within the system as shown by the auxiliary gage 12. 13 represents a piston rod within the cylinder 9, having an extension 13^a provided with an eye 14. The eye 14 may have secured thereto a cord 14^b, which passes over suitably arranged pulleys 14^c, and is connected to a damper-lever 14^c, which is suitably counter-weighted as indicated at 14^d. The piston rod passes through the cylinder head 15 and an adjustable stuffing box 16 and extends nearly to the bottom of the chamber, and on

the end is mounted the piston head 18. This head at the end of the piston stroke strikes the stops 19, leaving an opening 20 between the bottom of the piston and the bottom 21 of the cylinder.

An exhaust channel 22 is positioned within the casting, opening at 23 at the bottom and communicating at the top 25 with a passage 24 in the main valve casting 26.

Referring now to the main valve casting 26 shown in Fig. 3, 27 represents a main chamber into which steam enters from the steam pipe 4. In the top of the casting is a cylindrically threaded opening 28, in the bottom of which is threaded a renewable bushing 29 with a central bore 30 therethrough, the top of the bore forming a valve seat 31. The top of the opening 28 is protected by a threaded plug 32, having a central threaded bore 33. A bushing 33^a is fitted within the bore and a screw nut 33^b provided at the top. Within the chamber 75 below the bushing 29 is an enlarged bore 34, the lower walls of which consist of a central circumferential depending flange 35 within an enlarged exhaust chamber 36, opening on to the bottom of the plate 37. 80

Mounted within the chamber 36, below the circumferential flange 35 is a plunger 38 adapted to strike, at the end of its stroke, stops 39 on the bottom plate 37, thus forming a supplemental chamber 40 below the bottom of the plunger. The plunger is extended upwardly as shown at 41, the upwardly extending walls being slightly distant from the inner periphery, forming a passage 42 between the chambers 40 and 36 90 and permitting the passage of steam from one chamber to the other.

The plunger stem 43 extends up within the chamber 34 and the valve stem 44 passes through the bushing 29. The main check valve 45 on top of the stem is adapted to seat on the valve seat 31. The valve head 46 extends upwardly, entering into within the bore 33 below the bushing 33^a and is surrounded with a spring 47, serving to hold 100 the valve on its seat.

A spring 48 surrounds the flange 35 and rests on the top of the plunger, the upper end of the spring resting against the top of the chamber 36. A port 49 is provided within 105 the stem 43 which is uncovered by the down-

ward movement of the plunger 38, communicating with the passage 49^a opening into the chamber 36 as shown in Fig. 2.

The chamber 27 extends through the casting and terminates in a corresponding chamber 50 within a threaded bushing 51, screwed within the upper portion of the casting. The upper edges of this bushing are beveled, forming a valve seat for the supplementary ball check valve 52 which is normally held in engagement with the seat by means of a spring 53 within the bushing 54, screwed into the side of the casting. A screw nut 54^a is positioned at the end of the bushing and covered by screw cap 55, providing an opening through which the adjusting screw 56 passes.

A passage 57 extends from the interior of the chamber 34, communicating with a passage 58 in the top of the main cylinder opening into the top of the cylinder above the piston head.

A passage 59 is provided within the valve casting communicating at its lower end with the chamber 40 and at its upper end with the chamber 60 in the interior of the bushing 54 and back of the ball 52.

Referring now to the operation of my device, when steam is admitted through the governor valve, pressure is created in the chamber 27 tending to seat the check valve 45 and also tending to unseat the ball check valve 52. Steam under pressure passes by the ball check valve 52 into the chamber 60 and down the passage 59 into the chamber 40 underneath the plunger 38 and tends to force the plunger upward, unseating the check valve 45 thus permitting the steam to flow gradually through the passage 57 into the cylinder 17, and gradually forcing the piston down, thus closing the damper when the boiler pressure rises.

When the pressure falls, the ball check valve 52 gradually becomes seated, preventing the further passage of steam. The steam pressing against the plunger 38 escapes between the sides of the plunger and the walls of the chamber into the chamber 36 and out through the exhaust port 24. As the plunger 38 is forced down by the spring 48, the check valve 45 becomes seated, preventing further ingress of steam into the cylinder and the port 49 is uncovered by the downward movement of the plunger, enabling the steam within the cylinder to escape through the port and into the chamber 36, and out through the exhaust 22, thus permitting the piston to rise and open the damper.

When the boiler pressure is registered on the main gage 7 the valve 11 is turned up slowly so as to put the regulator in operation. The further adjustment of the valve 11 permits the regulator to work at any desired pressure. The device can be per-

manently set at any working pressure and will then operate in a graduated manner in about one pound variation. By the use of the screw 33^a I can regulate longitudinal movement of the valve 45 and prevent any excess length of stroke.

By the use of my device I am able to operate directly on fluid pressure without any supplemental water supply. Any excess water of condensation will be forced out into the cylinder and through the exhaust in the operation of the device without building up any water column. It is also to be noted that by the use of the renewable valve seats shown, much greater efficiency is secured, as after the seats become worn, the bushing may be quickly renewed.

It will be noted that I have produced a very sensitive valve that operates in a graduated manner and with great power, the sensitiveness being in no way effected by the power exerted and in which all of the parts are readily accessible and renewable. While I have shown a specific device and specific means by which the desired results may be accomplished, it is clear that there are numerous variations and modifications that will occur to those skilled in the art and that can be made in the mechanism of parts without in any way departing from the spirit of my invention.

The cylinder 9 and piston 18 are in effect a power cylinder and piston, the passage 57 affording communication between the cylinder and source of fluid pressure. The valve 45 is in effect a main check valve controlling the passage 57. The cylinder 36 and piston 38 constitute a controlling cylinder and piston for controlling the main check valve 45. The passage 59 connects the controlling cylinder with a source of fluid pressure. The valve 52 is a pressure reducing valve. When the controlling piston 38 opens the main check valve, the controlling piston will be subjected to the pressure of the fluid which passes the main check valve, through the bore 30 in the bushing 29. The passage 49^a is an exhaust passage, which is completely closed simultaneously with the initial opening of the main check valve, and is initially opened simultaneously with the complete closing of the main check valve.

I claim:

1. In a regulator the combination with a cylinder and power controlled piston operating therein, a source of fluid pressure, means for utilizing said pressure to regulate the movement of said piston, said means comprising a main valve casting containing a main chamber and supplemental chamber communicating with the cylinder above the piston and an exhaust chamber, a valve controlling a passage between said main and supplemental chambers and a check valve controlling a passage between said main

chamber and said exhaust chamber, a piston mounted in said exhaust chamber and extending into said supplemental chamber and adapted to engage and operate said 5 main valve.

2. In a regulator the combination with a cylinder and power controlled piston operating therein, a source of fluid pressure, means for utilizing said pressure to regulate the movement of said piston, said means comprising a main valve casting containing a main chamber and supplemental chamber communicating with the cylinder above the piston and an exhaust chamber, a valve 10 controlling a passage between said main and supplemental chambers and a check valve controlling a passage between said main chamber and said exhaust chamber, a spring held piston mounted in said exhaust chamber and extending into said supplemental chamber and adapted to engage and operate said main valve.

3. In a regulator the combination with a cylinder and power controlled piston operating therein, a source of fluid pressure, means for utilizing said pressure to regulate the movement of said piston, said means comprising a main valve casting containing a main chamber and supplemental chamber communicating with the cylinder above the piston and an exhaust chamber, a spring controlled main valve controlling a passage between said main and supplemental chambers and a spring controlled check valve 30 controlling a passage between said main chamber and said exhaust chamber, a spring held piston mounted in said exhaust chamber and extending into said supplemental chamber and adapted to engage and operate 40 said main valve.

4. In a regulator the combination with a cylinder and power controlled piston operating therein, a source of fluid pressure, means for utilizing said pressure to regulate the movement of said piston, said means comprising a main valve casting containing a main chamber and supplemental chamber communicating with the cylinder above the piston and an exhaust chamber, a valve 45 controlling a passage between said main and supplemental chambers and a check valve controlling a passage between said main chamber and said exhaust chamber, a piston mounted in said exhaust chamber and extending into said supplemental chamber having a passage communicating with said chamber and adapted to engage and operate said main valve.

5. In a regulator the combination with a cylinder and power controlled piston operating therein, a source of fluid pressure, means for utilizing said pressure to regulate the movement of said piston, said means comprising a main valve casting containing a main chamber and supplemental

chamber communicating with the cylinder above the piston and an exhaust chamber, a valve controlling a passage between said main and supplemental chambers and a check valve controlling a passage between 70 said main chamber and said exhaust chamber, a piston mounted in said exhaust chamber and extending into said supplemental chamber having a passage communicating with said chamber and adapted to engage 75 and operate said main valve, the stem of said main valve normally closing the entrance to said passage.

6. In a regulator the combination with a cylinder and power controlled piston operating therein, a source of fluid pressure, means for utilizing said pressure to regulate the movement of said piston, said means comprising a main valve casting containing a main chamber and supplemental chamber 80 communicating with the cylinder above the piston and an exhaust chamber, a spring controlled main valve controlling a passage between said main and supplemental chambers and a spring controlled 85 check valve controlling a passage between said main chamber and said exhaust chamber, a spring held piston mounted in said exhaust chamber and extending into said supplemental chamber, having a passage 90 communicating with said chambers, the stem of said main valve normally closing the entrance to said passage and adapted to engage and operate said main valve.

7. In a regulator the combination with a cylinder and power controlled piston operating therein, a source of fluid pressure, means for utilizing said pressure to regulate the movement of said piston, said means comprising a main valve casting containing 100 a main chamber and supplemental chamber communicating with the cylinder above the piston and an exhaust chamber, a valve controlling a passage between said main and supplemental chambers and a check-valve 105 comprising a ball and a renewable seat controlling a passage between said main chamber and said exhaust chamber, a piston mounted in said exhaust chamber and extending into said supplemental chamber and adapted to engage and operate 110 said main valve.

8. A regulating device comprising a power cylinder and piston, and means for controlling said piston comprising a passage 120 affording communication between said cylinder and a source of fluid pressure, a main check-valve controlling said passage, a controlling cylinder and piston for controlling said main check-valve, a passage 125 connecting said controlling cylinder with said source of fluid pressure, a pressure reducing valve in said passage, and means whereby when said controlling piston opens said main check-valve said controlling pis- 130

ton will be subjected to the pressure of the fluid which passes said main check-valve.

9. A regulating device comprising a power cylinder and piston, and means for controlling said power piston, comprising a passage affording communication between said piston and a source of fluid pressure, a main check-valve controlling said passage, a controlling cylinder and piston for controlling said main check-valve, a passage affording communication between said controlling cylinder and said source of fluid pressure, a reducing valve in said passage, a passage affording communication between said power cylinder and the exhaust, and valve means controlled by said controlling piston whereby said exhaust passage is completely closed simultaneously with the initial opening of said main check-valve, and

20 is initially opened simultaneously with the complete closing of said main check-valve.

10. A controlling device comprising a power cylinder and piston, and means for controlling said piston, comprising a pas-

sage affording communication between said power cylinder and a source of fluid pressure, a main check-valve controlling said passage, a passage affording communication between said power cylinder and the exhaust, valve means controlling said exhaust passage, a controlling cylinder and piston for controlling said main check-valve and said exhaust valve, a passage affording communication between said controlling cylinder and said source of fluid pressure, a reducing valve in said passage, and means whereby when said controlling piston opens said main check-valve, said controlling piston will be subjected to the pressure of the fluid which passes said main 40 check-valve.

In witness whereof I have hereunto subscribed my name in the presence of two witnesses.

JOHN M. LARSON.
